UNITED STATES PATENT OFFICE.

ARTHUR H. MARTIN, OF BUFFALO, NEW YORK, ASSIGNOR OF ONE-HALF
TO C. E. B. LAMSON, OF TOLEDO, OHIO.

ATTACHMENT FOR TYPE-WRITING MACHINES.

No. 819,778.

Specification of Letters Patent.

Patented May 8, 1906.

Application filed January 25, 1905. Serial No. 242,630.

To all whom it may concern:

Be it known that I, ARTHUR H. MARTIN, a citizen of the United States, residing at Buffalo, in the county of Erie and State of New York, have invented a new and useful Improvement in Attachments for Type-Writing Machines, of which the following is a specification.

This invention relates more particularly to devices for attachment to type-writing machines for holding a second or supplemental ink-ribbon in suitable relation to the primary ink-ribbon and record-sheets to enable the production of duplicate records without the employment of a carbon or manifolding sheet.

The principal objects of the invention are to provide a desirable and efficient holder or shield of simple construction which will support and guide the supplemental ink-ribbon in proper relation to the primary ink-ribbon and record-sheets and will cause the two record-sheets to pass on opposite sides of the supplemental ink-ribbon when inserting them in the machine without any manipulation or changing of position of the supplemental ribbon or parts of its holder, to provide simple means for preventing impressions on the reverse side of the outer record-sheet, and to provide the supplemental ink-ribbon holder with simple means to prevent the ribbon or holder from catching the front edges of the record-sheets and preventing the ready insertion of the sheets into the machine.

In the accompanying drawings, Figure 1 is a plan view of a supplemental ink-ribbon attachment embodying the invention, showing by full and broken lines portions of the carriage of a type-writing machine to which the attachment is applied. Fig. 2 is a transverse section, on an enlarged scale, of the ribbon holder or shield, showing the platen, portions of the carriage, primary ink-ribbon, and record-sheets by broken lines. Fig. 3 is an end elevation, on an enlarged scale, of the attachment and a portion of the type-writer carriage. Fig. 4 is a fragmentary section, on an enlarged scale, of the supplemental ink-ribbon holder or shield. Fig. 5 is a perspective view, on a reduced scale, of the supplemental ink-ribbon holder or shield.

The attachment comprises a shield, holder, or guide, which partially encircles the platen or feed-roll of the type-writer to support and

guide the supplemental ink-ribbon, separate 55 the record-sheets, and facilitate their insertion into the machine, and means for attaching or securing this supplemental ink-ribbon holder or shield in place on the carriage of the type-writer. The ribbon holder or shield 60 hereinafter described and shown in the drawings is designed and proportioned especially for use on the well-known Remington machine, and the holders or shields for other makes of machines may differ therefrom, as 65 required in matters of the size and arrangement of certain of the parts. The form and construction of the attaching devices for the holder or shield will also be varied as required for different makes of machines.

The supplemental ribbon holder or guide A (shown in the drawings) is curved longitudinally or is of trough-shape in cross-section, being of a width to loosely embrace the platen P, with which it is to be used, and is of 70 substantially the length of the platen. It is made of some suitable thin smooth material having the requisite stiffness to retain its form. Sheet-celluloid answers well for the purpose; but other material could be used. 75 The holder or guide is supported on the type-writer carriage in position to embrace or inclose that portion of the platen adjacent to which the primary ink-ribbon R is located and is provided at its opposite ends with openings 80 or guides b, through which the supplemental ink-ribbon R' passes and is held from lateral displacement. The holder or guide occupies a position between the primary ink-ribbon and platen, and when the machine is primed one 85 record sheet or paper X is located inside of the holder or guide between the supplemental ink-ribbon and the platen, while the other record sheet or paper Y is located outside of the holder or guide between the primary and 90 supplemental ink-ribbons. The holder or guide is open or slotted lengthwise at B between the ribbon-guides b to allow the supplemental ink-ribbon to be forced against the inner record-sheet to produce the second 95 record. The holder or guide is also provided with holes c and c' or is open at opposite sides of the ribbon-slot B at suitable points to allow the presser-rolls of the carriage, which are shown at d and d' by broken lines, to bear 100 against the record-sheets and press them against the platen to enable the feed of the sheets in the usual manner by turning the 105

platen. The presser-rollers are differently arranged in different makes of machines, and consequently the location and size of the holes or open spaces $c\ c'$ will vary in the holders or guides for different machines to properly accord with the different arrangements of the presser-rolls. In the holder or guide shown the holes c at the rear side of the platen are of oval shape, while those, c' , at the front side are triangular, with the bases of the triangles adjacent to the ribbon-slot B and the inclined edges c^2 of the triangular holes at the opposite ends of the holder or shield diverging forwardly and upwardly. By reason of these shapes and arrangement of the holes their edges will not catch the edges of the record-sheets and interfere with their ready insertion into the machine, as rectangular holes and holes of other shapes would do.

20 D represents a thin flexible guard-web, which bridges the ribbon-slot and underlies the supplemental ink-ribbon. Thin textile material answers well for the guard-web. The holder or guide A is preferably made of two thicknesses or superposed layers of material cemented or otherwise secured face to face and the rear edges of the supplemental ink-ribbon and guard-web extend in between the two thicknesses of the holder or guide at 25 the rear edge of the ribbon-slot, as shown in Fig. 4. The guard-web is cemented or secured to the holder or guide at opposite sides of the ribbon-slot, while the ribbon is disconnected and free to be moved longitudinally.

30 As the rear edges of the ribbon and guard-web are inclosed by the overlapping portions of the two thicknesses of the shield, they cannot engage the front edges of the record-sheets, which are inserted from the rear, as indicated by the arrow in Fig. 2. As the guard-web is secured to the opposite edges of the ribbon-slot, it holds these edges from spreading and distorting the shape of the guide, and as it overlaps the front edge of the slot it 35 effectually prevents the outer record-sheet from striking and catching on said edge, and it also prevents the ink-ribbon from sagging down through or working out of the ribbon-slot. The guard-web also prevents the supplemental ribbon from making impressions on the reverse side of the outer record-sheet; but as this could be prevented by using a ribbon inked on one side only or backed by some material to prevent its inking the outer sheet 45 this last-mentioned function of the guard is not so important as the others.

40 A thin narrow flexible tape or band E is preferably cemented or otherwise secured at its front edges to the front edge of the ribbon-slot and underlies the front edge of the supplemental ink-ribbon. This tape or band allows the ribbon to sink into the ribbon-slot sufficiently to prevent it from striking and smearing the inner record-sheet, but covers 50 the front edge of the ribbon-slot so as to pre-

vent the inner record-sheet from engaging and catching the latter. It will thus be seen that the holder or guide A also constitutes a guide for properly directing the two record-sheets on opposite sides of the supplemental 70 ink-ribbon when priming the machine.

In the construction shown in the drawings the ribbon holder or guide is supported by two rods F, which pass through loops f at the edges of the holder or guide and rest on the 75 end pieces of the carriage-frame, being held stationarily in place by suitable brackets G, arranged at the ends of the carriage and to which the ends of the supporting-rods are detachably secured, as by nuts g, screwed on the 80 threaded ends of the rods which pass through slots g' in the brackets G. The brackets pass under the platen-shaft, which, together with the rods F, hold the brackets from vertical movement. By tightening the nuts g the 85 brackets are clamped against the ends of the carriage. The slots g' in the brackets are elongated, thus enabling the proper adjustment of the latter and the holder or guide on the carriage. The brackets G rotatably support spools H for the supplemental ink-ribbon which passes through slots g^2 in the brackets and is attached to the spools. Automatic mechanism could be provided for feeding the supplemental ribbon; but as this 90 ribbon moves longitudinally with the carriage the type strike it throughout a considerable portion of its length, and it is sufficient to turn one or the other of the ribbon-spools by hand once in a while to present a new portion 100 of the ribbon to the type.

The holder-guide is put in place by inserting one edge thereof (before the supporting-rods are attached) between the platen and the presser-rolls d' and rotating the platen in 105 much the same manner as the record-sheets are ordinarily inserted. The rods F are then inserted in the edge loops of the holder and attached to the brackets G. The holder is a fixture to the carriage when once attached, 110 but can be readily detached when not desired by removing the rods F and feeding the holder or guide out by the rotation of the platen. No manipulation of the attachment is required to insert and remove the record-sheets after it is adjusted and secured to the 115 carriage.

The attaching devices shown and above described are of a construction and arrangement suitable for applying the ribbon holder or guide to a Remington type-writer, and they 120 can be differently constructed and arranged, if necessary, for different makes of machines.

I claim as my invention—

1. The combination with a type-writing-machine platen, and devices for pressing the record-sheets against the platen, of a guide which is stationarily supported adjacent to the platen and has a portion extending to a position to allow two record-sheets to be in- 125 130

- 5 serted between the platen and presser devices on opposite sides of the guide without moving the guide, an ink-ribbon supported adjacent to the platen, said guide being constructed to allow the presser devices to press the record-sheets against the platen and having parts which direct the record-sheets to opposite sides of said ink-ribbon, substantially as set forth.
- 10 2. The combination with a type-writing-machine platen, and devices for pressing the record-sheets against the platen, of a curved guide which partially surrounds the platen and separates two record-sheets, said guide 15 providing open spaces which allow the presser devices to press the record-sheets against the platen, an ink-ribbon supported adjacent to the platen, and parts on said guide arranged to direct the record-sheets to opposite sides of 20 said ink-ribbon, substantially as set forth.
- 10 3. The combination with a type-writing-machine platen, and devices for pressing the record-sheets against the platen, of a curved guide which partially surrounds the platen 25 and separates two record-sheets, said guide providing open spaces which allow the presser devices to press the record-sheets against the platen, and an ink-ribbon, said guide having means for supporting said ink-ribbon adjacent 30 to the platen, and portions arranged to direct the record-sheets to opposite sides of said ink-ribbon, substantially as set forth.
- 10 4. The combination with a type-writing-machine platen, and devices for pressing the record-sheets against the platen, of a curved 35 guide which partially surrounds the platen and separates two record-sheets, said guide providing open spaces which allow the presser devices to press the record-sheets against the 40 platen, an ink-ribbon, and a guard located between said ink-ribbon and the outer record-sheet, said guide having portions arranged to direct the record-sheets to opposite sides of said ink-ribbon and guard, substantially as 45 set forth.
- 10 5. In an attachment of the character described, a substantially trough-shaped guide which partially incloses the type-writer platen and has guides at its ends for an ink-ribbon, a ribbon-slot between said guides, and open spaces at opposite sides of said ribbon-slot, substantially as set forth.
- 10 6. In an attachment of the character described, a substantially trough-shaped guide 55 which partially incloses the type-writer
- platen and has guides at its ends for an ink-ribbon, a ribbon-slot between said guides, oval-shaped openings at one side of said ribbon-slot, and triangular openings at the opposite side of said ribbon-slot, substantially as 60 set forth.
7. In an attachment of the character described, a guide which partially surrounds the type-writer platen and has a slot for an ink-ribbon, and portions at one edge of said 65 slot which overlap the adjacent edge of the ink-ribbon to direct record-sheets to opposite sides of the ribbon, and means overlapping the opposite edge of said ribbon-slot to prevent the engagement of the latter with the 70 record-sheets, substantially as set forth.
8. In an attachment of the character described, a guide which partially surrounds the type-writer platen and has a slot for an ink-ribbon, and portions at one edge of the 75 slot which inclose the adjacent edge of the ribbon, and a guard which is inclosed by said portions at one edge of the ribbon-slot and overlaps the opposite edge of the ribbon-slot, substantially as set forth.
- 80 9. In an attachment of the character described, a guide which partially surrounds the type-writer platen and has a slot for an ink-ribbon, and portions at one edge of said slot which inclose the adjacent edge of the ribbon, a guard which is inclosed by said portions at one edge of the ribbon-slot and overlaps the opposite edge of the ribbon-slot, and a band which is secured to the opposite edge 85 of said ribbon-slot and extends in between 90 said ribbon and guard, substantially as set forth.
10. In an attachment for type-writing machines, the combination of a curved guide adapted to partially surround the platen and 95 separate two record-sheets and provided with openings through which the presser devices press the record-sheets against the platen, an ink-ribbon retained in position by said guide, said guide having parts arranged to direct 100 the record-sheets to opposite sides of said ink-ribbon, and means for supporting the guide in position to partially surround the platen, substantially as set forth.

Witness my hand this 24th day of January, 1905.
